UNITED STATES PATENT OFFICE.

JAMES H. GRAY, OF NEW YORK, N. Y.

OPERATING MECHANISM FOR ELECTRIC FURNACES.

1,376,758.

Specification of Letters Patent.

Patented May 3, 1921.

Application filed April 12, 1919. Serial No. 289,567.

To all whom it may concern:

Be it known that I, JAMES H. GRAY, a citizen of the United States, residing in the city, county, and State of New York, have 5 invented certain new and useful Improvements in Operating Mechanism for Electric Furnaces, of which the following is a specification.

Electric furnaces of the type used in treating steel and iron are generally arranged to tilt from an upright to an inclined position for emptying the furnace, withdrawing slag and other purposes. On account of the general use of a three-phase current, these furnaces usually have three electrodes. The electrodes are quite heavy, each weighing over two tons in the larger furnaces. They are arranged to be lowered or raised for the purpose of striking or breaking the arc, and during the operation of melting or treating steel they are moved upward and downward short distances for the purpose of regulating the amount of current flowing by increasing or decreasing the length of the arc. Usually 25 they are supported and lifted by cranes mounted on the furnace and movable upward and downward, or by cables passing up over sheaves and leading to winding motors mounted on the furnace. Such arrangements put an excess weight on the shell of the furnace and require heavy auxiliary supporting members. Also the heat and fumes coming from the furnace are destructive to the motor and to the gearing generally used 30 for reducing the speed between the motor and the electrodes.

My invention provides a mechanism for operating the electrodes by which the motor or other source of power can be fixed 40 and mounted on a stationary structure so as to avoid the disadvantages of the old style mechanism. At the same time the electrodes may be held in fixed position with reference to the furnace while the latter is being 45 tilted.

The accompanying drawings illustrate different embodiments of the invention.

Figure 1 is a plan;

Fig. 2 is a side elevation, omitting certain 50 guide sheaves;

Fig. 3 is a section on the line III—III of Fig. 2;

Figs. 4, 5 and 6 are diagrams showing separately the three operating cables of the previous figures;

Figs. 7 and 8 are fragmentary views in plan and in vertical section of a modified arrangement;

Fig. 9 is a plan, and Fig. 10 a side elevation illustrating another arrangement of 60 sheaves;

Figs. 11, 12 and 13 are respectively a plan, a face elevation and a side elevation illustrating still another arrangement of sheaves.

Referring first to Figs. 1 to 6, the furnace 65 1 is provided with three electrodes 2 each of which is clamped in a holder in the end of a bus bar 3 connected by flexible cables 4 with a transformer 5 from which the current is conveyed to the electrodes. Columns 70 6 are mounted on the side of the furnace and carry at their upper ends longitudinal beams 7 on which is supported a cross-beam 8 extending over the side of the furnace. On the beams 7 and 8 there are supported 75 pairs of sheaves 9 and single sheaves 10 located above the electrodes and the bus bars. Each electrode is supported by cables 11 attached to the ends of the bus bars alongside the electrode, running up and over the 80 sheaves 9 and thence to blocks 12, where their ends are fastened. Cables 13 are attached to the bus bars near their inner ends and pass up and over the guide pulleys 10 and thence to the blocks 12 where their ends are 85 also fastened. The blocks 12 thus serve as points of attachment for the means for supporting and raising or lowering the bus bars and electrodes. The furnace has a discharging spout 14, Fig. 1, at one side and a rear 90 charging door 15, with additional charging doors at the sides if desired, and is arranged to rock or turn about an axis indicated by the dotted line 16, Fig. 2, and the point 16, Fig. 3. The angle 17, Fig. 3, indicates the 95 extent to which the furnace is turned from an upright to a tilted position.

The blocks 12 are held in the bight of certain operating cables in such a way that the tilting of the furnace neither raises nor 100

lowers the electrodes. At the same time these operating cables can be lengthened or shortened by suitable motors to lower or raise the electrodes during the operation of the furnace. The blocks 12 are provided with guide pulleys 18, 19 and 20 identical with each other but differently numbered to better explain their operation. The cross-beam 8 has at its inner end a short upright 10 21 on which is pivotally supported a block 22 carrying a set of three pulleys at each of its opposite ends. Three motors 23 (Fig. 3) are arranged to drive in any usual or suitable way drums 24. The motors with 15 their gearing and drums are mounted on a wall 25 which houses the transformer. From the first drum a cable 26 passes up and over a guide pulley 27 fixed on the supporting wall 25, thence around a pulley 28 on 20 one end of the block 22, around pulley 20 of the first electrode, and back to a pulley 29 on the same axis with the pulley 28, and around this pulley and thence to a fixed support 30 mounted also on the supporting wall 25, its end being fixed to the support 30. The next operating cable 31 passes over a fixed guide pulley 32 thence over a pulley 33 between the pulleys 28 and 29, around this and to and around the pulley 19 which supports the second electrode, to a pulley 34 at the opposite side of the block 22 and around this and to the fixed support 30, where its end is fastened. The third operating cable 35 passes over a guide pulley 36 thence to a pulley 37 on the pivoted block, to the pulley 18 which supports the third electrode, back to a pulley 38 on the same axis with the pulley 37 and thence to the fixed support 30 where its end is fastened. Thus, as will 40 appear more clearly in Figs. 4, 5 and 6, two of the pulleys on one end of the pivoted block 22, namely 28 and 29 carry the operating cable 26 to the correspondingly located pulley 20, two pulleys 37 and 38 at the opposite 45 end of the pivoted block carrying the operating cable 35 to the opposite supporting pulley 18 for the third electrode, and pulleys 33 and 34 at opposite ends of the pivoted block carrying the operating cable 31 for the 50 intermediate supporting pulley 19. Thus the strain on the two ends of the pivoted block is balanced and the operating cables do not introduce any tendency to turn this pivoted block during the working of the furnace.

When the furnace is tilted through the angle 17, Fig. 3, the cross-beam 8 is carried with it and moves to the position shown in dotted lines. The operating cables passing 60 through this block tend to hold it always in the parallel lines extending from the fixed guide pulleys 27, 32 and 36, to the points of attachment of the cable ends to the fixed support 30. As the furnace turns the pivotal 65 center of the block 22 will describe an arc

carrying it slightly above the line of parallel movement. The angle of the operating cables passing through the block is so arranged that the longitudinal axis of the block, as the furnace is tilted, will reach a position at 70 right angles to the vertical axis of the furnace and then, as the tilting movement continues, will take angular position in the opposite direction to that which it had, at the beginning of the movement. Preferably the 75 direction of the cables is normal to the median line 39 between the two sides of the angle 17; so that in the tilted position the center of the block 22 will be as far to one side of this line as it is to the other side of this line in the starting position, and so that the two extreme positions of the pivotal center of the block will be on a line parallel with the cables passing through it. For example, if the furnace be designed to tilt to 80 an angle of 40 degrees from the vertical, then the line 39 stands at one-half this angle with the vertical and the operating cables from the fixed support 30 should run at one-half this amount or an angle of 20 degrees from 85 the horizontal, which is the same thing as saying that the direction of the cables must be at a right angle to the line 39 which bisects the angle 17. Any departure from this rule will mean a lengthening of the portions 90 of the operating cables between the pivoted block and the guide pulleys at the right and between said block and the fixed support 30 at the left, which will cause a raising of the electrodes. Within a small limit, such a 95 variation is not objectionable.

The motors are used only for forcibly raising or lowering the electrodes. During the tilting movement described they are stationary and hold the drums 24 stationary. 105 The cables are wound around the drums and carry counter-weights 40 at their lower ends which are normally a determined distance above the floor 41 or other support provided for them. Each counter-weight 110 may have the weight of the corresponding electrode holder, bus bar and flexible cable, plus the average weight of the electrode; or it may be heavier or lighter than the sum of such weights. If it is lighter than the 115 opposing force it will still put sufficient tension on the cable to cause it to bind on the drum, thus locking the cable when the drum is locked or lifting the electrode when the drum is turned in proper direction by the 120 motor. The length of the cable 26, or the distance of the counter-weight above the floor 41 is such that when the electrode holder reaches the desired upper end of its stroke, the counter-weight will rest on the 125 floor. This will loosen the cable on the drum and although the motor may continue to operate, the electrode holder will not be moved beyond its normal travel,—a movement which would result in breaking the 130

cable or some other part of the furnace. If the counter-weight be considerably heavier than the opposing forces, nevertheless the weight of the electrode holder and connected parts will be sufficient to give the cable the necessary tension to cause it to bind on the drum, so that there will be no movement except as the drum is rotated, and the turning of the drum in the proper direction will 5 lift the weight and allow the electrode holder to descend. The turning of the drum in the opposite direction of course lifts the electrode holder and lowers the counter-weight until it strikes the floor or other rest. It 10 will be seen therefore that the function of the counter-weight is largely that of a take-up for the tension on the cable, with a limited movement which releases the tension at the desired point. 15 This arrangement has advantages over those previously used, especially in the matter of safety. The motors are usually actuated by the electric current which is automatically regulated in accordance with the 20 conditions within the furnace, and the motor continues to operate in any one direction as long as those conditions persist. It has sometimes happened that an electrode rested on the scrap in the furnace or on the bottom 25 of the furnace without the predetermined amount of current flowing through the electrode; the automatic regulators then working to loosen the cables (to permit the electrodes to descend) which, after being unwound to their limit, and having their ends fastened to the winding drum, have been wound up in the other direction, lifting the electrode and breaking the mechanism. Such an accident is avoided by my arrangement 30 of cables and weights because if the electrode rests on the scrap or on the bottom of the furnace the tension in the cables is removed by a continued operation of the motor in the lowering direction, and they 35 no longer bind on the drum; so that the motors may continue to operate without effect.

The arrangement in Figs. 7 and 8 differs merely in the arrangement of the pulleys 50 in the pivoted block 22, and in the arrangement of the cables passing through it. Here the cable 26 runs over pulleys 42 and 43 in line with each other on opposite ends of the block 22, the bight of the cable between 55 the pulleys 42 and 43 passing to the electrode pulley 20. The cable 31 passes over pulleys 44 and 45 in line with each other at opposite ends of the pivoted block 22, the bight of the cable passing over the pulley 19. 60 Similarly the cable 35 passes over pulleys 46 and 47 and the bight of it over pulley 18.

The mode of operation and the functioning of the parts similar to those of Figs. 1 to 6.

65 According to Fig. 9 a pivot block 48 is

used which differs slightly from that of the previous figures. It is mounted on trunnions in a pair of upright posts 8^a (see Fig. 10) and is provided with three pairs of pulleys, one pair at the center and one pair 70 at each end. The first cable 26 will pass around the pulley 49 to and around the pulley 20 and thence to and around the larger pulley 50 which is loosely mounted on the same axis with the pulley 49. The cable 31 75 will pass in a similar way around the two intermediate pulleys of the pivoted block, and around the intermediate electrode supporting pulley 19. And the third cable 35 will pass around the two pulleys at the opposite end of the pivoted block and around the pulley 18. The pulleys within the block 80 48 are made of different sizes so as to cause the cables to clear each other as they pass behind through the rear portion of the block. 85

In all the foregoing designs, where the cables pass in a straight line from the supporting pulleys at the right to the pivoted block and from said block to the fixed ends at the left, there is a slight lengthening of 90 the portion of the cable in question as the block swings away from its supporting position, until it reaches its middle position, after which the cable is shortened and becomes, at the end of the movement, of its 95 initial length; these lengths of cable being bent out of their original straight lines from the guide pulleys to the fixed ends. The departure is greatest at the middle point of the arc 17^a, Fig. 8. The positions of the 100 pulleys 27, 32 and 36 and of the fixed ends of the cables may be so arranged that in the upright position of the furnace the cables will be, not in a straight line as shown, but in a bent line; the block 22 in its 105 starting position being depressed below a straight line by distances equal to one-half the offset caused by the arc; so that in the center point of the tilting movement it will be equally offset on the opposite side of the 110 straight line. Thus the variation from a straight line will be only one-half that occasioned with the arrangement of Fig. 8 where the cables stand in a straight line at the beginning and end of the movement. 115 This offset movement pulls the cable and lifts the electrode, no matter whether the departure from a straight line be upward or downward. Such an arrangement therefore 120 would result in first lowering the electrodes by a trifling distance and then raising them to the starting position at the end of the movement. Total movement of an electrode in either case is very trifling, about one-tenth of an inch in the arrangement of Figs. 125 3 and 8 and about one-twentieth of an inch in the alternative arrangement. It is desirable to have this movement very slight because when the furnace is tilted from its vertical position there is considerable friction 130

involved in any movement of the electrode with relation to the furnace. A movement of one-twentieth or even one-tenth of an inch is not enough to be seriously objectionable, but the cables may be so arranged that there will not be any movement, even theoretically.

In the construction of Figs. 11 to 13 these cables extend always in the same arc about 10 the center 16, so that as the block 51 swings from an upright to an angular position the cables remain unchanged in length. A rack or support 52 is attached to the wall 25 of the transformer room or some other support.

15 It is in the form of an arc struck from the center 16 about which the furnace tilts. It underlies the several operating cables 26, 31 and 35. The block 51 is fixed on the cross-beam 8 of the furnace and carries pulleys 53 and 54 over which the cable 35 passes to and from the electrode supporting pulley 20; pulleys 55 and 56 over which the cable 31 passes to and from the electrode supporting pulley 19; and pulleys 57 and 58 over which 20 the operating cable 26 passes around the electrode supporting pulley 18. The pulleys 53 and 58 are arranged in pairs on separate blocks as shown or various other styles of mounting may be used for them.

25 Though I have described with great particularity of detail certain embodiments of my invention, yet it is not to be understood therefrom that the invention is restricted to the particular embodiments disclosed. Various 30 modifications thereof in detail and in the arrangement of the parts may be made by those skilled in the art without departure from the invention as defined in the following claims.

35 40 What I claim is:

1. The combination with a tilting electric furnace of mechanism for adjusting electrodes in said furnace, said mechanism comprising a motor mounted on a stationary support and transmission means between the motor and the electrodes adapted to hold the latter in substantially the same position with reference to the furnace when the furnace is tilted as when it is upright.

45 50 55 2. The combination with a tilting electric furnace of mechanism for adjusting electrodes in said furnace, said mechanism comprising a motor mounted on a stationary support, and lifting cables from said motor to the electrodes, said cables being of substantially the same effective length in the tilted position of the furnace and in its upright position.

60 65 3. The combination with a tilting electric furnace of mechanism for adjusting electrodes in said furnace, said mechanism comprising a motor mounted on a stationary support and operating cables extending from the motor to a fixed point and engaging in their bight electrode supports

4. The combination with a tilting electric furnace of mechanism for adjusting electrodes in said furnace, said mechanism comprising a motor mounted on a stationary support and operating cables extending from the motor to a fixed point and engaging in their bight electrode supports, the direction of said operating cables being such that their length is substantially unchanged as the furnace passes from an upright to a tilted position.

5. The combination with a tilting electric furnace of electrode-adjusting mechanism for said furnace, said mechanism comprising a motor mounted independently of the furnace and transmission means between the motor and electrodes, said motor and transmission means being arranged to hold the electrodes in substantially the same position with reference to the furnace when the furnace is tilted as when it is upright.

6. The combination with a tilting electric furnace of electrode-adjusting mechanism for said furnace, said mechanism comprising a motor mounted independently of the furnace and transmission means between the motor and electrodes, said motor and transmission means being arranged to hold the electrodes in substantially the same position with reference to the furnace throughout the 95 tilting movement of the furnace.

7. The combination with a tilting electric furnace of mechanism for adjusting electrodes in said furnace, said mechanism comprising a motor mounted on a stationary support and transmission means between the motor and the electrodes adapted to hold the latter in substantially the same position with reference to the furnace throughout the 100 tilting movement of the furnace.

105 8. The combination with a tilting electric furnace of mechanism for adjusting electrodes in said furnace, said mechanism comprising a motor mounted on a stationary support and operating cables extending from the motor to a fixed point and engaging in their bight electrode supports, the direction of said operating cables being at an angle with the horizontal equal to about one-half the angle through which the furnace tilts.

110 115 9. The combination with a tilting electric furnace of mechanism for adjusting electrodes in said furnace, said mechanism comprising motors mounted on a stationary support, drums operated by said motors and operating cables passing from the electrodes to and around said drums and carrying at their ends weights adapted to maintain them in frictional engagement with said drums.

120 125 10. An electric furnace having adjustable electrodes, motors, drums operated thereby, automatic regulators for said motors and cables for operating said electrodes, said cables passing to and around said drums, and weights on the ends of said cables adapted 130

to maintain them in frictional engagement with said drums.

11. An electric furnace having adjustable electrodes, motors, drums operated thereby, 5 automatic regulators for said motors and cables for operating said electrodes, said cables passing to and around said drums, weights on the ends of said cables adapted to main-

tain them in frictional engagement with said drums, and supports for said weights limiting the extent of movement of the cable through which the drum will frictionally engage it to lift the electrode. 10

In witness whereof, I have hereunto signed my name.

JAMES H. GRAY.
